UNITED STATES PATENT OFFICE.

CLARENCE F. BAYER, OF NEW YORK, N. Y.

DESIGN FOR A LORGNETTE.

44,554.

Specification for Design.

Patented Aug. 26, 1913.

Application filed December 30, 1912. Serial No. 739,415. Term of patent 7 years.

To all whom it may concern:

Be it known that I, CLARENCE F. BAYER, a citizen of the United States, residing at No. 87 Hamilton Place, in the city of New York, in the county of New York and State of New York, have invented a new, original, and ornamental Design for a Lorgnette, of which the following is a specification, reference being had to the accompanying drawing, forming part thereof.

The figure is a plan view of a lorgnette, showing my new design.

I claim:

The ornamental design for a lorgnette as shown.

CLARENCE F. BAYER.

Witnesses:

GEO. FASS,
M. HUDSON.
